FIG 2

FIG 1

WALTER H. BAUM
INVENTOR
BY Louis Casper
ATTORNEY

UNITED STATES PATENT OFFICE

116,488

DESIGN FOR A TEXTILE FABRIC

Walter H. Baum, New York, N. Y.

Application June 16, 1939, Serial No. 85,526

Term of patent 3½ years

To all whom it may concern:

Be it known that, I, Walter H. Baum, a citizen of the United States, residing in New York city, in the county of New York and State of New York, have invented a new, original, and ornamental Design for a Textile Fabric, of which the following is a specification, reference being had to the accompanying drawing, forming part thereof.

Fig. 1 is a plan view of a textile fabric showing my design, and

Fig. 2 is the reverse side thereof.

I claim:

The ornamental design for a textile fabric, substantially as shown.

WALTER H. BAUM,
